(57) **CLAIM**

The ornamental design for an information transceiver, as shown and described.

DESCRIPTION

FIG. 1 is a front, right side perspective view of an information transceiver, showing our new design;

FIG. 2 is a rear, left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side view thereof; and,

FIG. 8 is a left side view thereof.

The shadings in the figures show contour and not surface ornamentation.
